(57) CLAIM

The ornamental design for a race car, as shown and described.

DESCRIPTION

FIG. 1 is a front perspective view of the race car showing the present design.

FIG. 2 is a front view thereof.

FIG. 3 is a rear view thereof.

FIG. 4 is a right side view thereof.

FIG. 5 is a left side view thereof.

FIG. 6 is a top plan view thereof; and,

FIG. 7 is a bottom plan view thereof.

The broken lines shown are included for the purpose of illustrating the unclaimed portions of the race car and form no part of the claimed design.
